SELECTIVE DEVICE

Erwin P. Bancroft, Brooklyn, N. Y., assignor to
International Communications Laboratories,
Inc., Newark, N. J., a corporation of New York

Application November 20, 1931
Serial No. 576,262

25 Claims. (Cl. 178—33)

My invention relates to improvements in selecting devices suitable for use in printing telegraph or other similar systems wherein a multiplicity of selections is made from a code of signals, such as the five-unit or Baudot code.

The object of my invention is to provide a selecting device which is capable of operation at high speeds, which is quiet and reliable, and in which shocks usually associated with rapid operation have been reduced to a minimum.

Selecting devices which have heretofore been used in connection with printing telegraph and the like apparatus may, in general, be divided into two types; those in which the selection is made by means of permutation bars or discs, and those in which the so-called "chain" selection is used. In the latter, the selection is made by successively dividing a total number of selections by two, for example, into halves, quarters, eighths, sixteenths, thirty-seconds, until finally a particular selection is made. A chain type selector is shown in Pfannenstiehl Patent 1,583,365.

In the permutation bar type selector, all of the elements from which one is to be selected normally attempt to move into the selected position, but only the particular one in front of which an aligned group of slots appears is allowed to complete its selecting operation. Thus, for each selection, a large number of elements, from which one is selected, are moved and considerable power is wasted.

In the ordinary type of chain selector, the effect of loose bearings, slides, etc., is cumulative and may materially affect the accurate location of the final selected position. Each type, thus, has its disadvantages.

According to my invention, the principle of chain selection is used but has been applied in such a way that final selected position can be made with any desired degree of accuracy without, at the same time, requiring extreme accuracy during the intermediate selecting positions.

According to my invention, the elements from which one is to be selected are first divided into groups and the particular group selected, then the particular element in the selected group is determined. This element is then operated and caused to perform whatever function is assigned thereto.

I have shown my invention in a form suitable for use in connection with an ordinary typewriter wherein pull bars are substituted for the links which ordinarily operate the type bars and perform other functions necessary for the auto-

matic printing of messages either in tape or page form.

While my invention is particularly suitable to the operation of type-printing mechanisms, it is also suitable for operation as a switching device wherein the pull bars may serve to close contacts instead of operating type bars, or where-in the contacts may be closed directly by the means provided for selecting the pull bars. Thus, as many different circuits may be controlled over a single wire as there are combinations in the code employed.

A particular advantage of the selector which I have devised is that practically the entire operation is of a positive nature as contrasted with the permissive operation of the usual type of permutation selector.

The device as illustrated is controlled by five selecting magnets which respond in various combinations to the transmitted signals. Each selecting magnet controls a cam. Upon responding to the code signals, the magnets cause the cams to be brought into operative relation with a rotatable switching member which carries a plurality of slidable switches.

These switches are moved in accordance with their engagement with the operated cams and form various paths for a positioning or guide pin which is capable of being set to eight different positions. Associated with this guide pin are four selecting pins spaced apart so that a pin in its movement may be aligned with a corresponding pull bar in each of four separate groups of eight pull bars. As there are four of these selecting pins, each co-operating with eight pull bars, it follows that, by selecting a particular group and a particular pull bar in the group, thirty-two different pull bars may be operated one at a time.

Twenty-six of these pull bars may be used for printing the letters of the alphabet, reserving the others for performing other necessary functions in the recording of message text, such as the spacing forward of the tape; the shift of the platen from the lower case to the upper case to permit the printing of figures, punctuation and other special characters; the return of the platen to its normal position; and, in the case of page recording, the returning of the paper carriage to the beginning of a line, and the feed of the paper forward for a new line. When the message is to be recorded on a tape, some of the pull bars may be assigned to special characters of other special functions, as desired.

As stated, for the purpose of illustration, I have shown the apparatus as designed for operation with five selecting magnets. For this purpose, the signals received over a telegraph circuit may be distributed to the selecting magnets by any of the well-known start stop distributors such, for example, as that disclosed in United States Patent No. 1,205,248. The cams which are shown controlled by the selecting magnets might be arranged to be operated from a mechanical selector which, in turn, might be controlled by a single magnet or relay in a main telegraph or signalling line. For this purpose, the single magnet mechanical distributor disclosed in United States Patent No. 1,229,201 might be used.

Various features of my invention will be noted from the description to follow.

My invention is illustrated in the accompanying drawings wherein:

Fig. 1 is a plan of the essential parts of the device;

Fig. 2 is a view on line 2-2 of Fig. 1;

Fig. 3 is a view on line 3-3 of Fig. 1;

Fig. 4 is a view on line 4-4 of Fig. 1;

Fig. 5 shows a detail of the locking mechanism for the bails;

Fig. 6 shows a detail of one of the bails;

Fig. 7 shows a development of the surface of the rotatable switching cam;

Fig. 8 is an explanatory view showing the co-operation of the essential parts;

Fig. 9 is a modification of Fig. 5;

Fig. 10 shows a form of stop-start circuit.

Referring first to Fig. 1, the rotatable switching member 1 is mounted on shaft 2 and is arranged to be coupled to a constantly rotating shaft 3 by a clutch 4, which may be like that disclosed in United States reissue Patent No. 17,725 issued to F. G. Creed July 8, 1930.

Clutch 4 is under the control of a magnet 5 (see Fig. 4) and, when released by the energization of magnet 5, couples shaft 2 to the constantly rotating shaft 3.

A carriage 6, slidably supported in guides 7-7' (see Fig. 3) parallel to the axis of member 1, is provided with a stud 8 which engages grooves in the surface of the member 1 and is capable of being moved to any one of eight positions, through the interaction of stud 8 and the grooves in member 1, as will be described later.

The carriage 6 also carries four selecting pins 9, each having a shoulder or flange 10 which moves or slides in a groove of a corresponding bail 11, as best shown in Figs. 3 and 6.

Each of the four bails 11 consists of a grooved member 12 rigidly attached to a yoke having two downwardly extending arms 13, as shown in Fig. 6. The two arms of each yoke are rigidly fastened to a hollow shaft 14 which is rotatably supported on a fixed shaft 15. Each individual hollow shaft 14 has rigidly attached thereto an arm 16 which is adapted to engage with a cam 17 (see Fig. 3). The two cams 17 to the left in Fig. 1 are rigidly mounted upon a hollow shaft 18, while the other two cams 17 to the right in Fig. 1 are rigidly mounted on a hollow shaft 19. The bails 11 are thus grouped for operation in pairs, two being controlled by the cams on shaft 18 and two by those on shaft 19. A constantly rotating shaft 20 passes through these two hollow shafts 18 and 19 and is adapted to be coupled to either of these hollow shafts by the release of the corresponding single revolution clutch 21 or 22, similar to clutch

4 already referred to and associated, respectively, with the hollow shafts 18 and 19. The release of clutch 21 or 22 is effected by corresponding arms 23 or 24, when the latter are engaged by a cam 25 (Fig. 7) on the member 1, as will be described later. The release of either clutch 21 or 22 will cause shaft 18 or 19 to be rotated one revolution by the shaft 20 and thereby cause the rotation of their associated cams 17.

Prior to the coupling of shaft 18 or 19 to shaft 20 and depending upon the position of the slideable knife-edged cam 26 (see Figs. 5 and 7) on member 1, a locking bar 27 is moved either to the right or to the left as the cam 26 passes the projection 28 on bar 27. Locking bar 27 is supported from the lower guide 7' (Fig. 2) by means of screws 29 passing through elongated holes 27' in the bar, so as to allow lateral movement thereof.

The locking bar 27 is arranged to lock the bails 11 in pairs through the tongues 30 and 31. In the arrangement shown (see Fig. 5), if the bar 27 is moved to the right, the right-hand bail of each pair will be held against operation, while, if it is to the left, the left-hand bail of each pair will be held. Thus, depending upon the position of locking bar 27 and depending upon which of the shafts 18 and 19 is rotated, any one of the four bails 11 may be operated.

Fig. 3 also shows plainly how the arm 16 co- operates with cam 17. When a bail 11 is locked by the extension 30 or 31 on bar 27, its arm 16 does not move when the flat or cut-away portion of the cam 17 comes opposite the end of arm 16. The bails 11 are under constant stress of spring 11' to rotate in a counter-clockwise direction (Figs. 2 and 3).

Rigidly fastened to shafts 18 and 19, in addition to cams 17, are cams 32 and 33, respectively. Associated with each of cams 32 and 33 is a roller 34 carried by a yoke 35 pivoted at 36 and continually spring-pressed against cams 32 and 33 by springs 37 (Fig. 2). Mounted on the ends of yokes 35 are operating bails 38 and 39 (Fig. 1) arranged to engage notches 40 in pull bars 41.

Clutch members 21 and 22 are normally held against rotation by extensions 23' and 24' on bell crank levers 23 and 24, respectively. Levers 23 and 24 are pivoted at 42 and are spring-pressed into the position shown (Fig. 2) by springs 43. Levers 23 and 24 have extensions 44 and 45 arranged to co-operate with switch 25 (Fig. 7) on member 1. Switch 25 is mounted on slide 46 in member 1 and is moved to the left by restore cam 47, and to the right by cam 51 acting on roller 56, when cam 51 is released by its associated selecting magnet 50 (Fig. 7).

Thus, if the magnet associated with cam 51 is operated during the rotation of member 1, cam 25 will be moved to the right and will co-operate with extension 45 of bell crank 24 to release clutch 22 by moving the stop 24' out of engagement therewith, thereby releasing shaft 19 and its associated cams 17 and 33 for rotation. Immediately following the operation of bell crank 24 by cam 25, restore cam 47 acts to restore switch slide 46 and cam member 25 to their left-hand position. If, then, during the next revolution of member 1, the selecting magnet associated with cam 51 is not operated, cam 51 will not engage pin 56 on slide switch 46 and the latter will remain in its left-hand position. Under this condition cam switch 25 will co-operate with extension 44 of bell crank 23 to move stop 23' out of engagement with clutch 21,

thereby releasing the latter and its associated shaft 18 and cams 17 and 32 for rotation.

The angular location of cam member 25 on member 1 and of the extensions 44 and 45 of bell cranks 23 and 24 is such that the release of clutch 21 or 22 occurs near the end of the rotation of member 1 and at such a time that the depression in cams 17 will pass under the ends of levers 16 just as member 1 reaches its stop position. Member 1 is arranged to stop with guide pin 8 in one of the eight locating slots 201-208 on member 1. Thus, with member 1 in its stop position, each of the selecting pins 9 will be located in front of a corresponding pull bar 41 in each of the four groups. The particular pull bar 41 that is selected and operated is determined by the position of the locking bar 27 and the shaft 18 or 19 that is released for rotation.

Assume now that member 1 has reached its stop position, that clutch 22 has been released, and that the locking bar 27 is positioned as shown in Fig. 5. Shaft 19 will have been released for rotation, carrying with it cams 17 and 33. As cam 17 rotates, a depressed portion thereon will pass under the ends of arms 16 of the right-hand pair of bails 11, freeing both arms 16 for rotation under tension of spring 11'. Only the left-hand arm 16 of the pair will complete its movement, since the right-hand one of the pair is restrained by projection 30 on locking bar 27. The rotation of arm 16 will carry with it its associated bail 11, moving pin 9 associated with the latter to the left in Fig. 2. The movement of pin 9 will force the pull bar 41, in front of which the pin 9 is positioned, to the left, placing the notch 40 thereon under the operating bail 39.

When the pull bar 41 has been positioned with its notch 40 beneath operating bail 39, roller 34 will have reached the depressed portion of cam 33 and yoke 35, under tension of spring 37, will move downward, causing bail 39 to engage the notch 40 in pull bar 41 and pulling bar 41 downward. As soon as bail 39 has engaged pull bar 41, the end of arm 16 again rides up on the raised portion of cam 17 and restores pin 9 to its normal position, thereby leaving the carriage 6 free to be moved to a new position corresponding to the succeeding code signal.

Referring to Fig. 3, there will be five magnets 50 and their associated cams, although but one is shown. The location of the five cams 51, 52, 53, 54 and 55 with respect to switching member 1 is shown in Figs. 3 and 7.

As shown in Fig. 3, each magnet 50 is provided with an armature 57 pivoted at 58 and held in a retracted position by the tension spring 59. Each armature is provided with an arm 60 pivoted at 61 which engages a notch 62 in its associated cam 51, 52, 53, 54 or 55.

Each cam 51-55 is provided with tension springs 63 which tend to hold it in engagement with member 1 when released.

Fig. 10 shows the five magnets 50 and starting magnet 5 controlled by the line relay 300 and the commutator 301.

The line relay 300 responds to the transmitted impulses and causes the operation of the magnets in proper combinations in accordance with standard practice.

Referring to Fig. 7, which shows the developed surface of switching cam 1, slides 64, 65 and 66 are arranged to be moved toward the left by cam surfaces 53, 54 and 55 by means of rollers

or pins 56 individual to each of the slides. The cam surfaces 53, 54 and 55 are normally held out of the path of rollers 56 by means of latches 60 on armatures 57 of the selecting magnets 50. Each of these magnets, three in number, is operated by one of the selecting impulses. The switching member 1 normally rotates in the direction shown by the arrow. The operation of the magnet 50, controlling cam surface 53, will allow the latter to move into the path of roller 56 on slide 64. As switching member 1 rotates, slide 64 will be forced toward the left, placing the switch 67 carried thereby in such a position as to open a path for guide pin 8 toward the right. With the slide 64 in the position shown, the path of guide pin 8 will be toward the left. Thus, the operation or nonoperation of the magnet 50, controlling cam 53, will determine which of the two paths pin 8 will follow. Similarly, the operation of the magnet 50, controlling cam 54, will place the latter in a position to move slide 65 toward the left. Slide 65 carries switches 68 and 69 which, in turn, serve to further control the paths opened to guide pin 8. The operation of the magnet 50, which controls cam 55, will place the latter in a position to move slide 66 to the left. Slide 66 carries switches 70, 71, 72 and 73. Each of these switches, in turn, controls the choice of two paths for the guide pin 8. It will thus be seen that, by the operation of the magnets 50, controlling cams 53, 54 and 55 in varying combinations, the selecting guide pin 8 may be caused to take any one of eight final positions 201 to 208 inclusive. For example, if the magnets 50 controlling cams 53, 54 and 55 are operated in response to appropriate impulses of the signal, slides 64, 65 and 66 will be moved to the left providing a single continuous track for the selecting guide pin 8 to position 208. This single continuous track is formed with fixed cam 80 as one side and the other side being formed by movable cam 67, fixed cam 167, movable cam 69, fixed cam 169 and movable cam 73.

Cams 51-55 inclusive are restored to their normal latched positions by means of cams 74-78 inclusive on switching member 1. The slides 64, 65 and 66 are restored to their normal right-hand position by means of restore cam 48. Cam surfaces 79 and 80 serve to restore the guide pin 8 to the central position ready to enter either the right or left-hand slot opened by switch 67 during the first part of each revolution of the switching member 1.

Slides 46 and 49 are controlled, respectively, by cams 51 and 52 which, in turn, are controlled by individual selecting magnets 50, in the manner already described. Slides 46 and 49 are restored to their normal left-hand position by means of restore cam 47.

From the foregoing description, it is seen that two units of each code signal are utilized to choose, from four groups of selectable elements, the particular group in which a selected element is located. The remaining units of each code signal are used for determining the location of the selected element in the particular group.

Fig. 8 is an explanatory view showing the cooperation of the essential features which have been described in detail in the preceding figures.

The mechanism in Fig. 8 is controlled by the rotatable switching member 1 shown in Figs. 1 and 7. The pin 8 which engages the groove of member 1 is moved in accordance with the op-

eration of slides 66, 65 and 64 controlled by cams 55, 54 and 53, respectively.

The movement of pin 8 causes a corresponding movement of carriage 6 and of the four pins 9 carried thereby, and positions each one in alignment with a pull bar 41 of the associated group.

The cam 26 engages the projection 28 of the bar 27 and moves it either to the right or left, to lock the bails 11 in pairs by means of the tongues 30 and 31.

The cam 25 which engages portions 44 or 45 of arms 23 or 24 depending upon the operation of slide 46, operates clutch 21 or 22 as the case may be. We will assume arm 23 is operated and also that arm 27 is moved to the left by projection 28 engaging cam 26.

The movement of arm 27 to the left locks bail 11 to the extreme left by tongue 30 engaging arm 13, while bail 11, the third from the left, is also locked by tongue 31 engaging arm 13. The bails 11 second and last from the left are unlocked and free to move. The operation of arm 23 operates clutch 21 and shaft 18 rotates and causes the rotation of the two cams 17 to the left and also that of cam 32.

At this time the four pins 9 are in alignment with a pull bar 41 of their respective group. When the arm 16 of the second or unlocked bail 11 engages the flat surface of its cam 17, the bail moves forward and causes its pin 9 to engage and push forward the pull bar 41 with which it is aligned and place the notch 40 in line with bar 38. The arm 16 of the first bail 11 cannot engage the flat surface of its cam 17 as the tongue 30 of the bar 27 engages the arm 13 of the first bail and holds it in a locked position.

When roller 34 of arm 35 engages the flat surface of its cam 32, it is forced downward under the influence of spring 37 and engages the notch 40 of the pull bar 41 which is pushed forward by the pin 9 controlled by the second bail 11.

The operation of this particular bar 41 may either cause a character to be recorded or may close or open contacts. After the shaft 18 has made one rotation the clutch 21 is engaged by the extension 23' of arm 23 and stops the rotation of the shaft 18.

An operation similar to that described takes place when the cam 25 engages 45 of arm 24. In this event clutch 22 is operated and the portion of the device to the right is rendered operative.

The operation of the device is as follows:

We will assume that the three magnets 50, which control cams 51, 52 and 53 are operated in response to the line signals. In each instance the armatures 57 will be attracted, withdrawing the arms 60 from the notches 62 of their respective cams which, under the influence of springs 63, cause them to move toward the face of the drum or rotating member 1.

Cam 51 will be in the path of pin 56 on slide 46 and, upon engagement therewith, will cause slide 46 with cam 25 to move to the right.

Cam 52 will be in the path of pin 56 on slide 49 and, upon engagement therewith, will cause slide 49 with cam 26 also to move to the right.

Cam 53 will be in the path of the pin 56 on slide 64 and, upon engagement therewith, will cause slide 64 with switch 67 also to move to the left.

The member 1 is caused to rotate when magnet 5 attracts the armature 81, allowing the

clutch 4 (Fig. 4) to operate and allow the rotation of shaft 2 which carries the member 1.

The clutch is operated under control of the device for distributing the line signals to magnets 50 as shown in Fig. 10, or as disclosed in United States Patents Nos. 1,564,422 and 1,565-165 of December 8, 1925. During the rotation of member 1, cam 53 engaging pin 56 causes the switch 64 to move to the left, providing a guide or groove to the right for the pin 8. As the member 1 rotates, pin 8 enters the groove to the right of switch 67, to the left of switch 69, to the left of switch 72, to position 205.

The movement of pin 8 to this position also causes a corresponding movement of the four pins 9 carried by the carriage 6. In the position 205 each pin 9 is in alignment with the fifth pull bar 41 of its group.

During the rotation of member 1, the cam 51 engages pin 56 on slide 46, forcing the slide and its cam 25 to the right so it will engage the nose 45 of lever 24 which moves about the bearing 42 and causes the portion 24 to disengage the clutch 22, allowing cams 17 to rotate. Prior to this operation, cam 52 engages pin 56 on slide 49 and forces slide 49 carrying cam 26 to the right. Cam 26 engages extension 28 on locking bar 27 and forces it to the right, thus causing the T-shaped portions 30 and 31 to lock the arms 13 of the right-hand bails 11 of each pair, or the left-hand bails 11 of each pair. The other bails 11 of each pair are free and the one on the extreme right, Fig. 1, will operate when the depressed portion of its cam 17 passes under the end of arm 16 after shaft 19 has been released for rotation, as already explained. The operation of bail 11 moves its associated selecting pin 9 toward the selected pull bar 41 (the fifth one counting left to right in the right-hand group), forcing the latter under the operating bail 39.

After the operated pin 9 has positioned the pull bar 41 so that the notch 40 is under the operating bail 39, roller 34 of arm 35 engages the depressed portion of cam 25 and the arm 35 is forced downward under tension of spring 37 and causes the bail 39 to engage the notch 40 and causes the fifth pull bar 41 to be moved downward to print the proper character or to close the proper contact. As soon as bail 39 engages notch 40 and holds the pull bar 41 in the selected position, selecting pin 9 is restored to normal and carriage 6 is free to assume a new position in accordance with the succeeding code signal.

As soon as cams 51, 52 and 53 have performed their functions in moving slides 46, 49 and 64, they are restored by cams 74, 75 and 76, respectively, and locked in the restored positions by arms 60 engaging in notches 62.

During the rotation of member 1 and after cams 25 and 26 and switch 67 have performed their functions, slides 46 and 49 are restored to the left by cam 47 and slide 64 to the right by cam 48.

After a complete revolution of the member 1, the arm 81 engages the clutch 4 and the member 1 is brought to rest.

When the shaft 20 has completed its rotation, the clutch 22 is rendered operative and the shaft 19 is brought to rest by the clutch 22 engaging extension 24' of lever 24.

Guide pin 8 remains in the selected position until the beginning of the succeeding revolution of member 1, when cam surfaces 79 or 80 serve

to restore it to a position opposite the guide leading to switch 67.

When line signals are distributed to magnets 50, which operate cams 51 and 52 alone, then 5 none of the slides 64, 65 and 66 are moved and pin 8, during the rotation of member 1, will enter the guide to the left of switches 67, 63 and 70 and assume position 201. In this position, the selecting pins 9 will be brought into 10 alignment with the first pull bar 40 of each group, and the pull bar in the group to the right in Fig. 1 will be operated.

It is evident that, by operating the magnets 50 which control cams 53, 54 and 55 in various 15 combinations, a path for guide pin 8 can be opened to any of the positions 201-208 as desired, and the selecting pins 9 can be positioned in front of any of the pull bars 41 in each group.

20 The selection of a pull bar in the right-hand group, Fig. 2, has already been described. To select a pull bar in the second group counting from the right, it is only necessary to operate the proper combination of magnets 50 controlling cams 53, 54 and 55 and cam 51. Under 25 this condition locking bar 27 will be positioned to the right, freeing the left-hand bail 11 of each pair and locking the right-hand ones. Since with cam 51 operated clutch 22 will be released, the left-hand bail 11 of the right-hand pair will be operated and the pull bar in the desired group will be selected.

To select the left-hand group of pull bars it is only necessary to operate the proper combinations of cams 53, 54 and 55, since under this 35 condition the left-hand bail 11 of each pair will be free to operate and clutch 21 will be released, allowing shaft 18 to rotate. The second group from the left is selected by operating 40 cam 52 in combination with desired combinations of cams 53, 54 and 55, to select the particular pull bar desired. Under this condition the left-hand bail 11 of each pair will be locked, leaving the right-hand ones free to operate, and, 45 since clutch 21 will be released, allowing shaft 18 to rotate, the second bail from the left will operate.

The foregoing description shows how the pins 50 9 are brought into alignment with any one of the eight pull bars in their respective groups, how the particular group is selected, and how the particular pull bar selected is operated. As there are four pins 9, each capable of selecting any pull bar of its group, it follows that thirty- 55 two selections may be made.

While I have illustrated the operating mechanism as being divided into two parts, each under control of a separate clutch 21 or 22, it is obvious, as shown in Fig. 9, that a single operating mechanism controlled by a single clutch can be substituted by altering the locking arrangement for bails 11 so that only one of bails 11 will be free to move. This is done by adding a second locking bar 27, controlled in the same manner as the one shown but by a separate knife-edged cam on member 1, which takes the place of cam 25. The second locking bar 27 will have projections corresponding to projections 30 and 31 but so arranged that, in the 60 left-hand position, say, the left-hand pair of bails 11 would be locked, and in the right-hand position the right-hand pair would be locked. The secondary shaft, controlled by a clutch 21 and carrying four cams 17 and one cam 32, would be released by a projection member 1

each time member 1 made a revolution. The result would be the same as in the arrangement shown, that is, for each different arrangement of the two cams 25 and 26 on member 1, one and only one of the bails 11 will be operated. 80

Thus, two units of each code signal are utilized for determining the particular one of four groups in which the selected element is located. It is evident, however, that three units of each code signal could be used in a similar manner 85 to choose one group out of eight.

What is claimed is:

1. In a selector for a signalling system wherein the signals are composed of different permutations of a definite number of impulses of opposite polarity, magnets one for each impulse responsive in various combinations according to the permutations of incoming signals, a rotatable member provided with slidable switches, an adjustable pin, selectable elements, and means controlled by the magnets in response to a signal to position the slidable switches to determine a selected path according to the particular permutation of the incoming signal over which, by rotation of said member, said pin is movable into 95 a selected position thereby to select one of said elements.

2. In a selector for a signalling system wherein the signals are composed of different permutations of a definite number of impulses of opposite polarity, magnets one for each impulse responsive in various combinations according to the permutations of incoming signals, a rotatable member having slidable switches thereon, an adjustable pin, a plurality of elements, means controlled by the magnets in response to a signal to position the slidable switches to determine a selected path according to the particular permutation of the incoming signal over which, by rotation of said member, said pin is movable 105 into a selected position thereby to select one of said elements, and means rendered effective upon selection of said one element for operating it.

3. In a selector for signalling systems wherein the signals are composed of different permutations of a definite number of impulses of opposite polarity, magnets equal in number to the 110 number of impulses and responsive to incoming signals, a rotatable member having slidable switches thereon, selectable elements divided into groups, an operating pin for each group, a connecting bar through which said operating pins slidably extend, a guide pin fixed to said bar, means controlled by said magnets in response to a signal to position one or more of the slidable 115 switches to determine with other of the switches a selected path, according to the particular permutation of the incoming signal, over which said guide pin is movable into a selected position thereby to position each said operating pin in 120 alignment with a selected element of the respective groups, and means controlled by other of said slidable switches to cause selectively the longitudinal movement of one of said operating pins to operate the element in alignment therewith.

4. In a selector for signalling systems wherein the signals are composed of different permutations of a definite number of impulses of opposite polarity, magnets equal in number to the 125 number of impulses and responsive to incoming signals, a rotatable member provided with slid- 130 able switches, selectable elements divided into groups, an operating member for each group, a 135 guide pin connected to said operating members, 140

- means controlled by said magnets in response to a signal to position one or more of the slideable switches to determine with other of the switches a selected path, according to the particular permutation of the incoming signal, over which said guide pin is movable into a selected position thereby to position each said operating member in alignment with a selected element of the respective groups, and means controlled by other 10 of said slideable switches to select one of said operating members to operate the element.
5. In a selective device the combination of a plurality of groups of elements, a selecting pin for each group, means for moving said pins simultaneously an equal distance into alignment with corresponding individual elements of the respective groups, means for selecting and operating one of said pins, and means for thereafter operating the element in alignment with the operated pin.
15. In a selector for signal controlled apparatus wherein the signals are composed of different permutations of a definite number of impulses of opposite polarity, magnets one for each impulse simultaneously an equal distance into alignment with corresponding individual elements of the respective groups, means for selecting and operating one of said pins, and means for thereafter operating the element in alignment with the operated pin.
20. In a selector for signal controlled apparatus wherein the signals are composed of different permutations of a definite number of impulses of opposite polarity, magnets one for each impulse responsive in various combinations according to the permutations of the signals, selectable elements, a selecting member, means controlled by said magnets for moving said selecting member into alignment with, and for causing the operation of, the one of said selectable elements corresponding to the permutations of the incoming signal.
25. In a selector for signal controlled apparatus wherein the signals are composed of different permutations of a definite number of impulses, magnets one for each impulse responsive in various combinations according to the permutations of the signals, a selecting member, a guide member having for said selecting member a start point and a plurality of rest points, means for forming for said selecting member a free path between said start point and one of the rest points according to the permutation of the signal, and means responsive to said signal to cause relative movement between said selecting and said guide members first to position said selecting member at said start point, and then to advance said selecting member along said formed free path to the selected rest point corresponding to the permutation of the signal.
30. In a selector for signal controlled apparatus wherein the signals are composed of different permutations of a definite number of impulses, magnets one for each impulse responsive in various combinations according to the permutations of the signals, a selecting member, a rotatable member having on the periphery thereof a guide with a narrow entrance and a wide base divided into a plurality of slots, fixed and movable switches between said entrance and said slots, means responsive to a permuted signal so to set the movable switches during rotation of said rotatable member as to form with the fixed switches a free path for said selecting member from said entrance to the one of said slots corresponding to the permutation of the signals, and effective during the setting of the movable switches to move said selecting member to the guide entrance.
35. In a selector for signal controlled apparatus wherein the signals are composed of different permutations of a definite number of impulses of opposite polarity, magnets one for each impulse responsive in various combinations according to the permutations of the signals, a selecting member, a rotatable member having on the periphery thereof a guide with a narrow entrance and a wide base divided into a plurality of slots, fixed and movable switches between said entrance and said slots, means responsive to a permuted signal so to set the movable switches during rotation of said rotatable member as to form with the fixed switches a free path for said selecting member from said entrance to the one of said slots corresponding to the permutation of the signals, and effective during the setting of the movable switches to move said selecting member to the guide entrance.
40. In a selector for signal controlled apparatus wherein the signals are composed of different permutations of a definite number of impulses, magnets one for each impulse responsive in various combinations according to the permutations of the signals, a selecting member, a rotatable member having on the periphery thereof a guide with a narrow entrance and a wide base divided into a plurality of slots, fixed and movable switches between said entrance and said slots, means responsive to a permuted signal so to set the movable switches during rotation of said rotatable member as to form with the fixed switches a free path for said selecting member from said entrance to the one of said slots corresponding to the permutation of the signals, and effective during the setting of the movable switches to move said selecting member to the guide entrance.
45. In a selector for signal controlled apparatus wherein the signals are composed of different permutations of a definite number of impulses, magnets one for each impulse responsive in various combinations according to the permutations of the signals, a selecting member, a rotatable member having on the periphery thereof a guide with a narrow entrance and a wide base divided into a plurality of slots, fixed and movable switches between said entrance and said slots, means responsive to a permuted signal so to set the movable switches during rotation of said rotatable member as to form with the fixed switches a free path for said selecting member from said entrance to the one of said slots corresponding to the permutation of the signals, and effective during the setting of the movable switches to move said selecting member to the guide entrance.
50. In a selector for signal controlled apparatus wherein the signals are composed of different permutations of a definite number of impulses, magnets one for each impulse responsive in various combinations according to the permutations of the signals, a selecting member, a rotatable member having on the periphery thereof a guide with a narrow entrance and a wide base divided into a plurality of slots, fixed and movable switches between said entrance and said slots, means responsive to a permuted signal so to set the movable switches during rotation of said rotatable member as to form with the fixed switches a free path for said selecting member from said entrance to the one of said slots corresponding to the permutation of the signals, and effective during the setting of the movable switches to move said selecting member to the guide entrance.
55. In a selector for signal controlled apparatus wherein the signals are composed of different permutations of a definite number of impulses, magnets one for each impulse responsive in various combinations according to the permutations of the signals, a selecting member, a rotatable member having on the periphery thereof a guide with a narrow entrance and a wide base divided into a plurality of slots, fixed and movable switches between said entrance and said slots, means responsive to a permuted signal so to set the movable switches during rotation of said rotatable member as to form with the fixed switches a free path for said selecting member from said entrance to the one of said slots corresponding to the permutation of the signals, and effective during the setting of the movable switches to move said selecting member to the guide entrance.
60. In a selector for signal controlled apparatus wherein the signals are composed of different permutations of a definite number of impulses, magnets one for each impulse responsive in various combinations according to the permutations of the signals, a selecting member, a rotatable member having on the periphery thereof a guide with a narrow entrance and a wide base divided into a plurality of slots, fixed and movable switches between said entrance and said slots, means responsive to a permuted signal so to set the movable switches during rotation of said rotatable member as to form with the fixed switches a free path for said selecting member from said entrance to the one of said slots corresponding to the permutation of the signals, and effective during the setting of the movable switches to move said selecting member to the guide entrance.
65. In a selector for signal controlled apparatus wherein the signals are composed of different permutations of a definite number of impulses, magnets one for each impulse responsive in various combinations according to the permutations of the signals, a selecting member, a rotatable member having on the periphery thereof a guide with a narrow entrance and a wide base divided into a plurality of slots, fixed and movable switches between said entrance and said slots, means responsive to a permuted signal so to set the movable switches during rotation of said rotatable member as to form with the fixed switches a free path for said selecting member from said entrance to the one of said slots corresponding to the permutation of the signals, and effective during the setting of the movable switches to move said selecting member to the guide entrance.
70. In a selector for a signalling system wherein the signals are composed of different permutations of a definite number of impulses of opposite polarity, magnets one for each im-

pulse responsive in various combinations according to the permutations of incoming signals, permutation members positioned by said magnets according to the incoming signal, a rotatable member having thereon slideable switches set by said positioned permutation members during rotation of said rotatable member, cams on said member co-operating with a plurality of said switches to form a track, and a selecting member co-operating with the track so formed and moved thereby into a selected position during rotation of said rotatable member.

10. In a selector for a signalling system wherein the signals are composed of different permutations of a definite number of impulses of opposite polarity, magnets equal in number to the number of said impulses and responsive to incoming signals, permutation members positioned by said magnets according to the incoming signal, a rotatable member having thereon slideable switches set by said positioned permutation members during rotation of said rotatable member, cams on said member co-operating with a plurality of said switches to form a track, a selecting member co-operating with the track so formed and moved thereby into a selected position during rotation of said rotatable member, a plurality of work members arranged in groups, a plurality of axially movable bars one for each group moved simultaneously and transversely to the axis thereof by said selecting member to select a work member in each group predetermined by the selected positioning of said selecting member, means controlled by other of said switches to determine the one of the selected work members to be operated, and means rendered effective upon such determination to move the corresponding bar into engagement with the work member so determined and operating means for the work member so engaged.

11. In a selector for a signalling system wherein the signals are composed of different permutations of a definite number of impulses of opposite polarity, magnets equal in number to the number of said impulses and responsive to incoming signals, permutation members moved from one position to another position by said magnets according to the incoming signal, a rotatable member having thereon slideable switches set by said positioned permutation members during rotation of said rotatable member, cams on said member co-operating with a plurality of said switches to form a track, a selecting member co-operating with the track so formed and moved thereby into a selected position during rotation of said rotatable member, cams carried by said rotatable member and made effective by rotation thereof to restore said permutation members to said one position immediately after the setting of said slideable switches and before said selecting member reaches said selected position, whereby another signal combination may be set up on said permutation members before completion of the selecting function of the preceding signal.

12. In a selector for a signalling system wherein the signals are composed of different permutations of a definite number of impulses of opposite polarity, magnets equal in number to the number of said impulses and responsive to incoming signals, two-position permutation members normally latched in one position and unlatched and moved into said other position.

- upon response of said magnets according to the incoming signal, a rotatable member having thereon slidable switches set by said positioned permutation members during rotation of said rotatable member, cams on said member co-operating with a plurality of said switches to form a track, a selecting member cooperating with the track so formed and moved thereby into a selected position during rotation of said rotatable member, and cams carried by and made effective by rotation of said rotatable member to restore the unlatched permutation members to latched position before said selecting member reaches said selected position.
13. In a selector for a signalling system wherein the signals are composed of different permutations of a definite number of impulses of opposite polarity, magnets one for each impulse responsive in varying combinations according to the incoming signals, two-position permutation members moved from one position to another position by said magnets according to the incoming signal, a rotatable member having thereon slidable switches set by said positioned permutation members during rotation of said rotatable member, cams on said member co-operating with a plurality of said switches to form a track, a selecting member co-operating with the track so formed and moved thereby into a selected position during rotation of said rotatable member, cams carried by said rotatable member and made effective by rotation thereof to restore said permutation members to said one position before said selecting member reaches said selected position, and means made effective by rotation of said rotatable member to restore the set slidable switches to the initial position thereof.
14. In a selector for a signalling system wherein the signals are composed of different permutations of a definite number of impulses of opposite polarity, magnets one for each impulse responsive in varying combinations according to the incoming signals, two-position permutation members moved from one to another position by said magnets according to the incoming signal, a rotatable member having thereon slidable switches set by said positioned permutation members during rotation of said rotatable member, cams on said member co-operating with a plurality of said switches to form a track, a selecting member cooperating with the track so formed and moved thereby into a selected position during rotation of said rotatable member, and stationary cams to engage the ends of and to restore the said slidable switches to the original position thereof during rotation of said rotatable member.
15. In a selector for a signalling system wherein the signals are composed of different permutations of a definite number of impulses of opposite polarity, magnets one for each impulse responsive in various combinations according to the incoming signals, two-position permutation members normally latched in one position and unlatched upon response of said magnets according to the incoming signal, springs for moving the unlatched permutation members into said other position, a rotatable member having thereon slidable switches set by said positioned permutation members during rotation of said rotatable member, cams on said member co-operating with a plurality of said switches to form a track, a selecting member co-operating with the track so formed and moved thereby during rotation of said member
- thereby into a selected position during rotation of said rotatable member, and cams carried by and made effective by rotation of said rotatable member to restore the unlatched permutation members to latched position before said selecting member reaches said selected position.
16. In a selector for a signalling system wherein the signals are composed of different permutations of a definite number of impulses of opposite polarity, magnets one for each impulse responsive in various combinations according to the incoming signals, permutation members positioned by said magnets according to the incoming signal, a rotatable member having thereon slidable switches set by said positioned permutation members during rotation of said rotatable member, cams on said member co-operating with a plurality of said switches to form a track, a selecting member co-operating with the track so formed and moved thereby into a selected position during rotation of said rotatable member, and cams on said rotatable member effective during rotation thereof whilst said slidable switches are being set to guide said selecting member into the selectively formed track.
17. In a selector the combination of a rotatable member, a plurality of magnets responsive to incoming signals composed of different permutations of a definite number of impulses of opposite polarity, a two-position cam for each magnet moved to one position by energization thereof and to the other position under control of the rotatable member, slidable switches on said member set in various combinations by said cams according to the energization of the magnets to form a track, and a selecting member co-operating with the track so formed and moved thereby during rotation of the rotatable member into a selected position.
18. In a selector for a signalling system wherein the signals are composed of different permutations of a definite number of impulses of opposite polarity, magnets equal in number to the number of said impulses and responsive in different combinations to incoming signals according to the permutations thereof, a rotatable member having two spaced fixed peripheral cams and a plurality of fixed and a plurality of movable cam switches disposed therebetween, a two-position cam for each magnet moved to one position by energization thereof and to the other position under control of the rotatable member, means co-operating with said cams to set the movable cam switches in various combinations according to the magnets energized whereby said movable cam switches and said fixed cam switches co-operate to form a track, and a selecting member co-operating with the track so formed and moved thereby during rotation of the rotatable member into a selected position.
19. In a selector for a signalling system wherein the signals are composed of different permutations of a definite number of impulses of opposite polarity, magnets equal in number to said number of impulses and responsive in different combinations to incoming signals according to the permutation thereof, two-position permutation members moved into one position by the magnets so responding, a rotatable member having thereon slidable switches set by said positioned members during rotation thereof, cams on said member co-operating with a plurality of said switches to form a track, a selecting member co-operating with the track so formed and moved thereby during rotation of said member

- to a selected position, and means carried by said rotatable member and effective during rotation thereof whilst the selecting member is being so moved to progressively restore the permutation members to the initial position thereof. 5
20. In a selector for signal controlled apparatus wherein the signals are composed of different permutations of a definite number of impulses of opposite polarity, magnets one for each impulse responsive in various combinations according to the permutations of the signals, selectable elements divided into groups, a selecting member for each group, means controlled by a plurality of said magnets for moving said selecting member simultaneously into alignment with one of the elements of each group, means controlled by other of said magnets for selecting one of said groups, and means rendered effective upon selection of the group and element to cause 10 operation of the selected element of the selected group. 15
21. In a selector for signal controlled apparatus wherein the signals are composed of different permutations of a definite number of impulses of opposite polarity, magnets responsive in different combinations according to the permutations of the signals, permutation members controlled by and to which the magnets transfer the received signal combination, a rotatable member, selecting switches thereon controlled by and to which the permutation members transfer the received signal combination during the rotation of said member, selectable elements divided into groups, a selecting member for each group, means controlled through the co-operation of several of the selecting switches for causing said selecting members simultaneously to select a selectable element of each group, means controlled by other of said selecting switches to select one of said groups, and means rendered effective upon selection of said group and element thereof to operate the selected element thereof. 25
22. In a selector according to claim 21, having means rendered effective by the rotation of said rotatable member for progressively freeing said permutation members and the several said switches immediately after transfer of the signal combination therefrom to receive another signal combination. 30
23. In a selector for signal controlled apparatus wherein the signals are composed of different permutations of a definite number of impulses of two different characters, magnets one for each impulse responsive in various combinations according to the permutations of the signals, a plurality of groups of selectable elements, a selecting member for each group, means controlled by said magnets for moving said selecting members simultaneously an equal distance determined by the permutation of the particular signal and into alignment with corresponding individual selectable elements of the respective groups, means for selecting and thereafter operating one of said selecting members, and means for thereafter operating the selected selectable element in alignment with the selected selecting member. 35
24. In a selector the combination of a rotatable member, electromagnetic means responsive to incoming signals composed of different permutations of a definite number of impulses of opposite polarity, a two-position cam for each impulse composing an incoming signal moved to one position by energization of said means and to the other position under control of the rotatable member, slideable switches on said member set in various combinations by said cams according to the polarity of the impulses of an incoming signal to form a track, and a selecting member co-operating with the track so formed and moved thereby during rotation of the rotatable member into a selected position. 40
25. In a selector the combination of a rotatable member, electromagnet means responsive to incoming signals composed of different permutations of a definite number of impulses of opposite polarity, slideable switches one for each impulse of an incoming signal mounted on said member, cam means controlled by said electromagnetic means to set the switches in various combinations in accordance with the polarity of the signal impulses to form a track, and a selecting member co-operating with the track so formed and moved thereby during rotation of the rotatable member into a selected position. 45
